(57) **CLAIM**

The ornamental design for an inverter alternating current busbar, as shown and described.

DESCRIPTION

FIG. 1 is a perspective view of an inverter alternating current busbar;

FIG. 2 is a rear view of the inverter alternating current busbar;

FIG. 3 is a front view of the inverter alternating current busbar;

FIG. 4 is a left side view of the inverter alternating current busbar;

FIG. 5 is a right side view of the inverter alternating current busbar;

FIG. 6 is a top view of the inverter alternating current busbar; and,

FIG. 7 is a bottom view of the inverter alternating current busbar.

The broken lines depict portions of the inverter alternating current busbar which form no part of the claimed design.
